UNITED STATES PATENT OFFICE.

THOMAS R. FERRALL, OF SOMERVILLE, MASSACHUSETTS.

DESIGN FOR A TACKLE-BLOCK.

SPECIFICATION forming part of Design No. 27,950, dated December 7, 1897.

Application filed August 18, 1897. Serial No. 648,729. Term of patent 14 years.

To all whom it may concern:

Be it known that I, THOMAS R. FERRALL, a citizen of the United States, residing at Somerville, in the county of Middlesex and State 5 of Massachusetts, have invented and produced a new and original Design for a Tackle-Block, of which the following is a full, clear, and exact description.

Reference is to be had to the accompanying 10 drawings, forming a part of this specification, in which similar characters of reference indicate corresponding parts in both the figures.

Figure 1 is a plan view of a tackle-block, 15 showing my new design; and Fig. 2 is an end view thereof.

As shown in the drawings, the leading feature of my design consists in the cheek-pieces of the block, elliptical in contour, with the ends extending substantially to a point, the cheek- 20 pieces having a circular ornamentation.

Referring particularly to the drawings, the cheek-pieces are shown as having their opposite edges 1 and 2 curved outward from end to end, with the meeting ends forming points 3 at the ends of the block. At approximately 25 the center of the cheek-pieces concentric rings are formed, and, as clearly shown in Fig. 2, the edges are transversely rounded or beveled, and in Fig. 2 it will also be seen that a head-block 4 is arranged between the cheek-pieces, but it is of less width than the cheek-pieces. 30

I claim—

The design for a tackle-block as herein shown and described.

THOMAS R. FERRALL.
